UNITED STATES PATENT OFFICE.

CHARLES H. BURTON, OF CLEVELAND, OHIO.

STEAM-ACTUATED VALVE.

SPECIFICATION forming part of Letters Patent No. 317,500, dated May 12, 1885.

Application filed June 4, 1884. (No model.)

To all whom it may concern:

Be it known that I, CHARLES H. BURTON, of Cleveland, in the county of Cuyahoga and State of Ohio, have invented certain new and useful Improvements in Steam-Actuated Valves, of which the following is a specification.

This invention relates to that class of steam-valves known as "steam-actuated valves;" and it consists in the peculiar construction and combination of parts, as hereinafter described and claimed.

In the accompanying drawings, Figure 1 is a vertical longitudinal section of a device embodying my invention. Fig. 2 is a view, part in plan and part in section, of the same in line 2 2, Fig. 1. Fig. 3 is a transverse vertical section of the same in line 3 3 of Fig. 1. Fig. 4 is a view, partly in perspective and partly in section, of the cylinder and valve-cases, showing the arrangement of steam-ducts and a "blind valve" for changing direction of steam in said ducts. Fig. 5 is a view in elevation of the blind-valve, looking in the direction of the arrow in Fig. 3, having outer wall removed to show interior.

A is a steam-cylinder. B is a steam-chest; C, the piston of steam-cylinder A. D is a cylindrical valve operating within the steam-chest B. E E are steam supply or feed ports leading from the ends of the cylinder A inwardly toward the middle portion of the steam-chest B. F is the exhaust. g is a port leading from the steam-chest B to the valve K, and g' is another port leading from the opposite end of steam-chest B to the valve K. This valve K constitutes my improvement in this present application. The parts of the device herein mentioned and preceding this valve are contained in my Patent No. 224,072, of February 3, 1880. Said valve K consists of a flat plate located in a chamber, k, attached to one side of steam-chest B, and slides upon the wall of said chamber next against the steam-chest. Its impinging face has an S-shaped groove cut into it, the upper arm of said groove arranged to register with port g, and the lower arm arranged to register with the other port, g', and the central arm of said groove registering with a port, g², leading from the steam-chest. The valve D in this construction is the same as that in my patent of

February 3, 1880. It is located within the cavity of the steam-chest B, and consists of four disks fixed upon a common shaft. The 55 end disks, D' D², constitute, respectively, the heads or ends of this valve. Through each of the heads D' D² is made a small hole or vent, d, through which steam may freely escape at all times, for the purpose of balancing the valve, 60 and providing a steam-cushion at each end thereof. The two middle disks, D³ D⁴, are located and constructed to regulate and control the passage of steam from the steam-chest B to the cylinder A through the ports E, and 65 also to regulate the exhaust of steam from the cylinder A.

K² is a longitudinal stem or shaft, attached to valve K for operating the same. Motion is imparted to the valve K through the agency 70 of the movements of boss K⁵, which is attached to the rod of the piston C. This boss K⁵, impinging alternately against the stops K³ K⁴, imparts an intermittent longitudinally-reciprocating motion to the valve K. The boss K⁵ 75 may be substituted by a lever pivoted between piston-rod and shaft K², and operated by stops on the piston-rod like those on shaft K². This would require that the S-shaped groove in the face of valve K be reversed, as seen at 80 s, Fig. 4, so that the same reciprocations of the valve K serve for changing direction of steam as by the other means.

The operation of my device is as follows: In Fig. 1 the parts are shown in the position 85 that they assume when the piston C is at its extreme left-hand throw. In this position steam will be fed through supply B' into valve-chamber k, thence up through and over through the ducts k' k², into the steam-chest 90 between the disks D' D³ of the valve D, through the left-hand port E to the left face of the piston C, while the steam from the right-hand face of said piston will be discharged through the exhaust by way of the right-hand 95 port E and the space in the steam-chest between the disks D³ D⁴, and finally through the exhaust F. In this position of parts the port g and the upper arm of the groove in the valve K have registered, so that steam has 100 escaped through said port from the right-hand side of the valve D, thus relieving the pressure of steam upon the opposite end having already

removed the valve D to the position shown in Fig. 1, where it has stopped the port g in such a manner as to prevent the escape of steam through it into the valve K. Steam now being received upon the left face of the piston C, will drive it to the right until the boss K⁵, striking the stop K⁴, will move the shaft K², with its valve K, to the right sufficiently to bring the port g' and the lower arm of the 10 groove in the face of the valve K into register, at which time steam will escape and be discharged from the left end of the valve D, which will cause it to move to the left, causing the disk D³ to cut off steam through the 15 left-hand port E, and, after it has passed over it, to permit the steam from the left of the piston C to discharge through this left-hand port E, and the space between the disks D³ 20 D⁴, out through the exhaust F. Meanwhile, steam will be admitted through the supply B', between the disks D⁴ D², through the right-hand port E to the right-hand face of the piston C, which will drive it to the position shown in Fig. 1. The holes d in the heads D' D² of 25 the valve D should not be so large as to permit of too free passage of steam, so that when the steam is exhausted from either end the pressure elsewhere upon this valve will cause

it to move in the direction of the exhaust, either to the right or left, as the case may be. 30 In practice these holes may be about one-sixteenth inch in diameter for a valve two inches in diameter. It will be noticed that this valve K exposes none of its ports to the chamber k, where the steam first enters, and is therefore 35 in that sense a blind valve. The pressure of steam in said chamber serves to bear upon and hold the valve upon its face.

Having described my invention, what I claim is—

1. The valve K, inclosed in a steam-chamber and having grooves or channels in its face arranged to register with ports g g' alternately, substantially in the manner and for the purpose specified.

2. The combination, with the main valve D, provided with the grooved pistons D' D² and intermediate pistons or disks, D³ D⁴, of the auxiliary valve K, provided with S-shaped groove communicating with the ports g g' and port g², 40 and the cylinder A, with its ports E E and exhaust F.
